UNITED STATES PATENT OFFICE.

FRANK D. ADAMS, OF AUBURN, CALIFORNIA.

LETTER AND BILL FILE.

SPECIFICATION forming part of Letters Patent No. 269,613, dated December 26, 1882.

Application filed June 8, 1882. (No model.)

To all whom it may concern:

Be it known that I, FRANK D. ADAMS, of Auburn, in the county of Placer and State of California, have invented a new and useful Improvement in Letter and Bill Files, of which the following is a full, clear, and exact description.

The object of my invention is to furnish a file for receiving letters, bills, and similar papers in a manner to allow convenient inspection of any bill or letter on the file; and, further, to combine with the file a device for fastening the bundle of bills or letters on its removal.

To that end my invention consists in the file constructed as hereinafter described and claimed.

Reference is to be had to the accompanying drawings, forming a part of this specification, in which similar letters of reference indicate corresponding parts in both the figures.

Figure 1 is a perspective view of my improved bill and letter file. Fig. 2 is a detail section, in larger size, showing the arrangement of the fasteners.

A is a base-plate, which is preferably formed of metal and attached permanently to a board, B. On the plate A are fixed posts *a a*, receiving in slots a cross rod or wire, *b*, the ends of which are bent up to form hooks *c c*, these hooks being tubular.

c c are the perforators, which are tubular, pointed at their ends, and attached to the plate A by being screwed into hollow slotted studs *d d* on the plate, whereby the perforators are held rigidly in an upright position. *f* is a guide-wire attached on plate A, to serve as a guide for placing the letters on the perforators. The cross-bar *b* fits loosely in the slots of the posts *a*, so that it is free to be raised up and down, and when in the downward position the ends of the hooks *c* take over the pointed ends of the perforators *e*, so that the perforators and hooks form a continuous wire and allow the letters to be turned over for the inspection of any one on the file.

When the bar *b* is raised the hooks are carried above the ends of the perforators, as shown in Fig. 1, and the bar may be then also turned backward, as shown by dotted lines, out of the way, to allow the removal or placing of the letters upon the perforators.

g is a handle on the bar *b*, for use in manipulating it; and *h* is a plate-spring taking against the projection on the bar, so as to hold the hooks in any position in which they may be placed.

The plate A is slotted, as shown at K, beneath the hollow studs *d*, to receive the heads of fasteners *i*. The studs are also slotted on one side, as shown. These fasteners are ordinary paper-clamps, of suitable length, and their folded ends extend upward into the perforators *e*.

To place a bill or letter on the file, the bar *b*, with the hooks *c*, is to be raised and turned back. The paper is placed against the guide-wire *f* and then pressed down upon the perforators, and the hooks being then returned to their place upon the perforators, the bills and letters are retained in place and may be turned over for inspection. When the file is filled, the bar and hooks are to be raised in the same manner and turned back, and the perforators then unscrewed from the studs *d* and drawn out, leaving the fasteners *i* in the bills or letters. The ends of the fasteners may then be turned down, and the bundle of papers thus fastened can be removed by sliding the heads of the fasteners from the slots K in the base-plate.

Having thus described my invention, I claim as new and desire to secure by Letters Patent—

1. The combination, with the slotted posts *a a* and hooks *c*, of the loose cross-bar *b*, whereby the ends of the hooks will take over the perforators and form a continuous wire, as described.

2. The combination, with the base-plate A and perforators *e*, of the slotted posts *a*, bar *b*, and tubular hooks *c*, substantially as described, for operation as set forth.

3. The combination of the perforators *e* and fasteners *i* with the slotted base-plate A, having the tubular slotted studs *d*, substantially as and for the purposes set forth.

FRANK D. ADAMS.
